UNITED STATES PATENT OFFICE.

MARTIN C. BERSTED, OF CHICAGO, ILLINOIS.

WRENCH.

1,109,032.

Specification of Letters Patent.

Patented Sept. 1, 1914.

Application filed November 17, 1913. Serial No. 801,335.

To all whom it may concern:

Be it known that I, MARTIN C. BERSTED, a citizen of the United States, and a resident of Chicago, in the county of Cook and State of Illinois, have invented certain new and useful Improvements in Wrenches, of which the following is a full, clear, and exact specification.

My invention is concerned with wrenches of the type in which the jaws are interchangeable, so that a plurality of jaws of different designs may be used with a single handle, and adjustable so that the jaws may assume a plurality of positions with reference to the handle, and is designed to produce a wrench of the class described which shall be simple and compact in its construction, and capable of being operated quickly and efficiently in all positions where such wrenches are employed.

To illustrate my invention, I annex hereto a sheet of drawings, in which the same reference characters are used to designate identical parts in all the figures, of which,—

Figure 1 is a side elevation of a wrench embodying my invention, with a portion thereof broken away; Fig. 2 is a central longitudinal section on the line A—A of Fig. 1; Fig. 3 is a view in cross section on the line B—B of Fig. 1; Fig. 4 is a cross section on the line C—C of Fig. 1; and Figs. 5, 6 and 7 are perspective views of different forms of jaws which I may employ in connection with my invention.

The handle of the wrench is formed of two parts, the larger part *a* having the thickened portion at the inner end terminated by the inclined offset *b*, while the somewhat enlarged circular outer end is provided with a circular offset *c*, which is adapted to serve as a bearing in the manner to be described. The smaller portion *d* of the handle is pivoted at *e* to the main portion, and its inner end is cut off at an angle to coöperate with the offset *b* to stop the pivoted portion when it is swung into the full-line position shown in Fig. 1, to secure the jaw in place. The shape of the outer end of the portion *d* corresponds in general to the shape of the outer end of the portion *a*, and it is provided with a circular recess *f* to permit the manipulation of the plunger in a manner which will be subsequently described. The head of the main

portion *a* of the handle has formed therein an aperture *g* which is of the general shape of an inverted T. Bored into the head is a cylindrical aperture *h* which intersects the T-shaped aperture *g* and extends, as seen in Fig. 2, almost as far as the size of the offset *c* will permit. Mounted to slide in this aperture *h* is the locking dog *j*, which preferably has the nose beveled on one side and square on the other, for a purpose which will be hereinafter described, and the inner portion of this dog *j* has a cylindrical aperture *k* bored therein to accommodate the helically-coiled expanding spring *l* inserted in its aperture and coöperating with the bottom of the recess *h* to hold the dog *j* yieldingly in its engaging position. This dog *j* has rigidly secured thereon or formed integrally therewith a milled circular flange *m*, and outside this is a reduced flange portion *n* which has two flattened sides *o* which are adapted to coöperate with the adjacent sides of the stem portion of the T-shaped aperture *g*.

The wrench jaws may, as shown in Figs. 5, 6 and 7, have any desired shape, but all of them are provided with annular portions *p* of substantially the same diameter as the head of the handle, and provided with a circular aperture *q* which is of the proper diameter to fit snugly over the offset *c*. On the interior of so much of this aperture as is practicable, I form recesses *r*, and it will be noted that as the jaw is adjusted to different positions, as indicated by the dotted lines in Fig. 1, the nose of the dog *j* coöperates with the different recesses to lock the same in position. By making one side of the nose of the dog *j* beveled, while the other is square, it is possible to ratchet the jaw of the wrench into different positions by simply swinging the handle. When the jaw has been ratched entirely to one side, it can be thrown back to the other side merely by seizing the milled flange *m* between the thumb and first finger and pulling it down to disengage the dog from the recesses *r*. Or, if it is desirable to lock the jaw from ratcheting in the direction it has been moving, all that is necessary is to withdraw the dog and turn it through 180°, and allow it to slip back into place under the tension of the spring *l*, when it will be ready to be used as a solid wrench, turning

in the same direction as before; or it can then be ratcheted back in the opposite direction.

What I claim as new, and desire to secure 5 by Letters Patent of the United States, is:

1. In a wrench, the combination with a two-part handle having a bearing lug projecting from the outer end of the main part, the other part extending outward the same 10 distance and permanently pivoted thereto being adapted to be swung over or away from said lug as desired, of a jaw having an aperture therein adapted to be fitted over the lug in various positions when the 15 swinging portion of the handle is withdrawn, and connections between said lug and the aperture of the jaw to hold the latter in any of the positions in which it is placed, substantially as and for the purpose described.

2. In a wrench, the combination of a two-part handle having a circular bearing-lug rigidly secured to and projecting from the outer end of the main part, the other part being adapted to be swung over or away from said lug as desired, of a jaw having a circular aperture with recesses in the periphery of the aperture and adapted to be fitted over the lug in various positions when 25 the swinging portion of the handle is withdrawn, and a sliding spring-pressed plunger mounted in the lug and having a nose adapted to coöperate with any of the above-mentioned recesses.

3. In a wrench, the combination with a two-part handle having a circular bearing-lug with a T-shaped recess therethrough rigidly secured to and projecting from the outer end of the main part, the other part 30 being adapted to be swung over or away from said lug, as desired, of a jaw having a circular aperture therein with recesses in the periphery of the aperture adapted to be fitted over the lug in various positions 35 when the swinging portion of the handle is withdrawn, and a sliding spring-pressed plunger mounted in the lug, having a nose adapted to coöperate with any of the recesses, and having flattened surfaces co-

operating with the sides of the narrower 50 part of the T-shaped recess to prevent the plunger from turning.

4. In a wrench, the combination with a two-part handle having a circular bearing-lug with a T-shaped aperture therein projecting from the outer end of the main part, the other part being adapted to be swung over or away from said lug, as desired, of a jaw having a circular aperture with recesses in the periphery of the aperture adapted to 55 be fitted over the lug in various positions when the swinging portion of the handle is withdrawn, a sliding spring-pressed plunger mounted in the lug, hollow at one end and having a nose at the other end adapted to 60 coöperate with the recesses in the jaw, a coöperating aperture in the lug into which the hollow end of the plunger may be forced, and a helically-coiled expanding 65 spring in said hollow end aperture.

5. In a wrench, the combination with a two-part handle having a circular bearing-lug with an aperture therethrough rigidly secured to and projecting from the outer end of the main part, the other part being 70 adapted to be swung over or away from said lug, as desired, the swinging part having another aperture registering with the aperture in the bearing lug when the handle is closed, of a jaw having a circular 75 aperture with recesses in the periphery of the aperture adapted to be fitted over the lug in various positions when the swinging portion of the handle is withdrawn, and a sliding spring-pressed plunger mounted in 80 the lug and having a nose adapted to co-operate with the recesses, and a flange which can be manipulated through the apertures in the swinging portion of the handle and the bearing lug.

In witness whereof, I have hereunto set my hand and affixed my seal, this 15th day of November, A. D. 1913.

MARTIN C. BERSTED. [L. S.]
